John Hartin

UNITED STATES PATENT OFFICE.

JOHN HARTIN, OF NEW YORK, N. Y.

IMPROVEMENT IN WATER-METERS.

Specification forming part of Letters Patent No. 9,746, dated May 24, 1853.

To all whom it may concern:

Be it known that I, JOHN HARTIN, of New York, in the county and State of New York, have invented certain new and useful Improvements in a Fluid-Meter; and I do hereby declare that the following is a full, clear, and exact description of the fluid-meter with the improvements, reference being had to the accompanying drawings and the letters of reference thereon, all of which form a part of this specification.

The same letters of reference always designate the same object or part of the meter in all the figures.

In the drawings, Figure 1 is a longitudinal vertical section. A is a cylinder. B is a piston. C is the piston-rod, to which is attached an arm, D, which plays by means of a pin in a slit in a connecting-piece, E, which operates a lever, F, to the top of which is attached a ball, G. H H are two slotted connecting-rods, which operate three sliding valves, I' I' I''. K K are passages for the fluid to enter into the cylinder. L L L L L are passages for the fluid to be discharged from the cylinder. M M are joints in the connecting-rods H H. N is an index for ascertaining how much fluid is discharged from the cylinder. O is a finger fixed to the piston-rod for marking the index. P is a sliding box for regulating the stroke of the piston and the quantity of fluid in the cylinder. Q is a screw by which the sliding box P is moved. R is a sliding piece to be regulated in conjunction with the sliding box P. S is a screw to set the sliding piece R. T T are two flexible metallic rings placed around the piston to cause it to move tight in the cylinder. U U are openings in the piston through which the fluid acts on the metallic rings T T.

Fig. 2 is a sectional end view through the center of the cylinder. A is the cylinder. I' is a sliding valve for opening and shutting the passages through which the fluid enters into the cylinder. K is a passage for the fluid to enter into the cylinder. L is a passage for the discharge of the fluid from the cylinder.

Fig. 3 is a perspective view of the piston. T T are two flexible metallic rings. U U U are openings through which the fluid acts on the metallic rings and forces them outward, thus causing the piston to move tight in the cylinder. V is a cut through the metallic ring to allow it to expand.

The nature of my invention consists in providing the cylinder inside with a sliding box or stop, P, which is adjusted in its position by a screw, Q, by which means I can limit the stroke of the piston by causing it to strike against the said box or stop for the purpose of preventing the pin in the arm D from straining upon the stop R in the slotted arm E after tilting the lever F. The sliding box P in the cylinder and the sliding piece R in the slotted connecting-piece E have to be regulated proportionally, so as to have the oscillating ball G, with its lever F, operate the valves properly. I make slits in the two connecting-rods H H, which operate the valves, and make likewise a slit in the connecting-piece E. By the combination of these two slotted connecting-rods H H and the slotted connecting-piece E with the oscillating ball G and lever F, I obtain a sudden change of the valves whenever the piston has moved to a certain place in the cylinder. I make the fluid itself cause the piston to move tight in the cylinder by means of openings U U U, Fig. 3, on the faces of the piston. These openings run obliquely, U U, Fig. 1, toward the inside of metallic rings placed in grooves around the piston. Through the said openings the fluid presses against the inside of the metallic rings (which are cut through in one place, as shown, V, Fig. 3) and causes them to expand and press tight against the cylinder. I place an index, N, Fig. 1, near the piston-rod, and a finger or point, O, on the piston-rod, by which means I ascertain how much fluid is drawn off from the cylinder.

To enable others skilled in the art to make and use my invention, I shall further describe its construction and operation.

I construct a cylinder, A, with its necessary passages, K K K L L L L, Fig. 1, for the fluid to enter and to be discharged through, and proper places for the valves, as shown in the annexed drawings. Into this cylinder, after it has been accurately bored inside, I fit a piston, B, tightly, allowing it to move freely. Around this piston I put flexible metallic rings fitted into grooves nicely. Said rings I cut off in one place, V, Fig. 3, so that they can expand. On the faces of the piston I make oblique openings toward the inside of the metallic rings. The rod of the piston passes through one end of the cylinder. At the other end of the cylinder, inside, I place

a round box, P, which is fitted closely around a projecting piece and made to slide on it by means of the regulating-screw Q. This box P is to limit the stroke of the piston. I place one sliding valve in the passage over the cylinder, I', Fig. 1, and two sliding valves at their proper places in the passages below the cylinder, I² I³. To the upper valve, I', I attach a connecting-rod, H, joined at M, said connecting-rod being slotted at the end and connected with a lever, F, by means of a pin on the lever passing through this slit. To the two lower valves I attach likewise a connecting-rod and connect it with the lever F in the same manner as the upper connecting-rod. To the piston-rod I fix a short arm, D, and connect this arm with the lever F by means of a slotted connecting-piece, E, and a pin on the arm D, which pin plays in the slit of the connecting-piece E. At the end of this slit I fit a sliding piece, R, to be operated by a screw, S. The piece R has to be regulated in conjunction with the sliding box P in the cylinder, for the purpose as hereinbefore stated. At the top of the lever F, I place a ball, G. I put an index, N, near the piston-rod and a point, O, on the piston-rod to mark the index.

Now, if the fluid enters through one passage at the top into the cylinder, it will force the piston along in the cylinder and at the same time act against those metallic rings on the piston and force them outward, thus preventing the leakage of the piston. When the piston is moved to a certain place in the cylinder, the piston-rod acts (by means of the arm D and its pin in the slit of the connecting-piece E) on the lever F, and carries the oscillating

ball G over the center, when the weight of the ball G carries the lever F down quickly and as quickly changes the valves. The top valve closes the passage where the fluid just entered one end of the cylinder, and opens the other passage for the fluid to pass into the other end of the cylinder. At the same time that the upper valve changes the two lower valves change also, one valve allowing the fluid which passed into the cylinder at one end to be discharged while the other valve is closed and the fluid is passing into the cylinder at the other end, thus causing the piston to move to and fro in the cylinder.

The slits in the connecting-rods H H of the valves are for the purpose of leaving the valves undisturbed until the oscillating ball G is carried over the center, when it causes the valves to change quickly.

The index N marks the quantity which may be discharged during one stroke of the piston. To ascertain how many cylinders of fluid have been drawn, another index must be attached to the meter.

Having thus fully described my improved fluid-meter, what I claim as my invention, and desire to secure by Letters Patent, is—

The adjustable box or stop P in one end of the cylinder for the piston to strike against, for the purpose of preventing the pin in the arm D from straining upon the stop R in the slotted arm E after the tilting of the lever F, substantially as herein set forth.

JOHN HARTIN.
